CLAIM

I claim the ornamental design for a chicken coop automatic door, as shown and described.

DESCRIPTION

FIG. 1 is a front perspective view of a chicken coop automatic door, showing my new design with a door in a raised position;

FIG. 2 is a rear perspective view of FIG. 1;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a top plan view of FIG. 1;

FIG. 8 is a bottom plan view of FIG. 1;

FIG. 9 is a front perspective view thereof, illustrated with the door in a lowered position; and,

FIG. 10 is a rear perspective view of FIG. 9.

The broken lines in FIGS. 2, 4 and 10 illustrate environmental matter that forms no part of the claimed design.
